P. GROEBER.

WALL PAPER.

No. 15,239.

Patented Aug. 12, 1884.

UNITED STATES PATENT OFFICE.

PAUL GROEBER, OF NEW YORK, N. Y.

DESIGN FOR WALL-PAPER.

SPECIFICATION forming part of Design No. 15,239, dated August 12, 1884.

Application filed April 11, 1884. Term of patent 3½ years.

To all whom it may concern:

Be it known that I, PAUL GROEBER, a citizen of the United States, residing in the city of New York, county and State of New York, have invented and produced a new and original Design for Wall or Ceiling Covering, which is especially intended as a frieze or dado.

The drawing represents a front plan view of the design.

It consists of an upper and lower narrow border, *a a*, having plain disks *b* displayed at regular intervals. The intermediate space between the two borders is filled in with a floral design, treated in the Venetian style, presenting open flowers *c* and budding flowers *d*, with palmatisected leaves and stems arranged in scroll-like forms. One leaf, *e*, has the usual position of the mid-rib a series of 'e bud-like bodies.

A peculiarity of this design is that neither the stems nor leaves are continuous, but detached, forming breaks and interruptions, even isolating portions of the design. The intermediate part of the pattern lying between the borders is shaded in parts not occupied by the design with horizontal lines *f* in close proximity.

I claim—

The design for a wall or ceiling covering, shown in the print accompanying this description.

PAUL GROEBER.
